UNITED STATES PATENT OFFICE.

LAFAYETTE F. BLEDSOE AND IVEY B. MORRIS, OF LANGDALE, ALABAMA.

SLACK-TWISTED-YARN PREVENTIVE.

Application filed July 2, 1923. Serial No. 649,003.

To all whom it may concern:

Be it known that we, LAFAYETTE F. BLEDSOE and IVEY B. MORRIS, citizens of the United States, residing at Langdale, in the 5 county of Chambers and State of Alabama, have invented certain new and useful Improvements in Slack-Twisted-Yarn Preventives, of which the following is a specification.

10 The present invention relates to textile machinery, and more especially to spinning and twister frames.

One object of the invention is to provide a device, to be associated with such frames, 15 that will prevent all looseness of the driving band.

Another object is to provide such a device which will keep the driving band under 20 yieldable tension so that it will at all times be sufficiently tight to perform efficiently in operation.

A further object is to provide such a device which can readily be incorporated into spinning and twister frames now in use, and 25 without the necessity of removing parts of the frame.

A still further object of the invention is to provide an arrangement of the driving band so that it will drive a larger number 30 of spindles than have hitherto been customary.

Another and important object of the present invention is to provide a device which, by acting on the driving band, will eliminate 35 practically all of the slack twisted yarn, make the yarn more uniform and eliminate a large part of the friction on the spindles.

Other objects and advantages will appear 40 from the following description, taken in connection with the accompanying drawings, which illustrate a preferred form of the invention. Various changes and modifications will occur to those skilled in the art, and the drawings are not to be construed as a definition 45 of the limits of the invention, reference being had to the accompanying claims for that purpose.

In the drawings,

Figure 1 is a side elevation, partly in section, of a ring spinning or ring twister frame 50 embodying the present invention.

Fig. 2 is a top plan fragmentary diagrammatic view illustrating a preferred arrangement of the runs of the driving band.

55 Referring more in detail to said drawings, and especially to Fig. 1, the numeral 1 design-

nates generally a straight or usual form of twister frame, provided with the driving cylinder 2 and the opposed spindle whorls 3.

Disposed below said whorls are the usual 60 spindle ladders 4, provided as shown, with a horizontal portion and usual upstanding flange 5. The driving band 6 passes around the driving cylinder 2, thence around four of said spindle whorls 3 and has a depending 65 run 7, the purpose and function of which will now be described.

In order to provide for the efficient driving 70 of four of said spindle whorls by the same driving band and in order to eliminate practically all slack twisted yarn and keep the driving band under a sufficient and yieldable tension the following means are employed.

A clamp block 8 is provided on its under- 75 side with a groove adapted to receive the up-standing flange 5 on the spindle ladder. The block 8 is provided with any suitable clamp-ing means, shown in the drawings in the form of a set screw 9, for clamping the block in its desired position upon the spindle ladder. A projection 10 extends from one side of the block 8 and is provided with a sub- 80 stantially horizontally arranged stud shaft 11 extending sideways upon one side of said projection. Pivotal secured to said stud shaft 11 is the arm 12 which carries at its outer end the tension pulley 13.

The tension pulley 13 is mounted to re- 85olve upon a short shaft 14 carried by said arm 12 and is preferably grooved about its 90 circumference to receive the driving band 7.

The tension pulley 13 is preferably made 95 of some relatively heavy material in order that by its weight, it may affect the tension upon the driving band, maintaining said band at substantially the same yieldable tension.

It will be seen that by providing such 100 tension upon the driving band 7 the same band may be satisfactorily and sufficiently used to drive four spindle whorls. As it has been generally customary to use the driving band to drive not more than two spindle whorls the above described arrange- 105 ment makes it possible to use one-half the usual number of driving bands.

It will further be seen that by maintaining 110 a proper tension upon the driving band the above described invention acts sufficiently to eliminate slack twisted yarn, making the yarn more uniform.

It will further be noted that a large part

of the weight of the tension pulley and its co-operating parts is carried directly by the driving band and the necessity of weighting down the parts whose weight is carried largely by the stud shafts is eliminated.

The tension pulley and its co-operating parts may, due to their construction, be applied and fixed in position, at any point along the spindle ladder without removing 10 or even temporarily altering any portion whatever of the twister frame.

I claim:

1. In a spinning or twister frame, a driving cylinder, spindle whorls, a driving band 15 between said spindle and whorls, a spindle ladder, and a slack-twisted yarn preventive for said frame comprising a grooved clamp provided with a set screw and adapted to receive the spindle ladder in said groove 20 and clamp it therein, an arm pivotally secured to said clamp for movement in a sub-

stantially vertical plane, and an idle pulley rotatably secured to said arm and associated with said driving band.

2. In a spinning or twister frame having 25 a spindle ladder, driving mechanism comprising a driving cylinder, a plurality of spindle whorls, and a series of driving bands each passing around said cylinder and four of said spindle whorls, a clamp secured 30 to said spindle ladder, an arm pivotally secured to said clamp and a weighted idle pulley associated with said arm and bearing on a run of said band which passes around said driving cylinder whereby the 35 entire weight of the pulley is upon the loop of the band, and little or no weight is upon the clamp.

In testimony whereof we affix our signatures.

LAFAYETTE F. BLEDSOE.
IVEY B. MORRIS.
